J. Herlong.

Cotton Planter.

Nº 116.
31/12/0.

Patented Jan. 15, 1861.

Fig. 2.

Inventor,
Daniel Sterling
Upon Munro & Co
Attorneys

UNITED STATES PATENT OFFICE.

DANIEL HERLONG, OF SANDY RIDGE, ALABAMA.

IMPROVEMENT IN COTTON-SEED PLANTERS.

Specification forming part of Letters Patent No. 31,120, dated January 15, 1861.

To all whom it may concern:

Be it known that I, DANIEL HERLONG, of Sandy Ridge, in the county of Lowndes and State of Alabama, have invented a new and Improved Cotton-Seed Planter; and I do hereby declare that the following is a full, clear, and exact description of the same, reference being had to the annexed drawings, making a part of this specification, in which—

Figure 1 is a longitudinal section of my invention, taken in the line *x x*, Fig. 2; Fig. 2, a horizontal section of the same, taken in the line *y y*, Fig. 1.

Similar letters of reference indicate corresponding parts in the two figures.

This invention consists in a novel and improved means for distributing the seed or discharging it from the hopper, whereby a uniform discharge of seed is insured and the seed-distributing device made to operate very evenly or regularly.

To enable those skilled in the art to fully understand and construct my invention, I will proceed to describe it.

A A represent the side pieces, the back ends of which are connected by a traverse-bar, *a*, and B is a hopper or seed-box, which is firmly secured between the front parts of the side pieces.

C C are two handles, which are attached to the back parts of the side pieces, A A, and D is a wheel, which is placed between the side pieces, A A, just back of the hopper or seed-box B, the axle *b* of said wheel having its bearings in the side pieces.

To each side of the wheel D there are attached pins *c*. These pins project horizontally from the wheel, and the pins at one side of it are in line with the centers of the spaces between the pins at the other side, as indicated clearly in Fig. 1, the dotted circles showing the position of the pins at the back side of the wheel.

E E are uprights, which are secured one to each side piece A, and to each upright a spring, F, is attached, said springs projecting down at the inner sides of the side pieces, A A, so that their lower parts will extend within the paths of the movement of the pins *c*.

To the lower end of each spring F there is attached by a joint, *d*, a pawl, G. These pawls engage with ratchets H H, which are on a shaft, I, that passes transversely through the

bottom of the hopper or seed-box B, and is provided with radial teeth *e*, which are within the hopper B, the ratchets H being at the outer side of the hopper, as shown clearly in Fig. 2. In the bottom *f* of the hopper or seed-box there is made a rectangular opening, *g*, which has a metal bar, *h*, at each side of it.

To the front part of the machine a furrow-share, J, is attached, and a coverer, K, is secured to the back part of the machine. The coverer is formed of a segment bar, *h*, attached to the lower ends of swinging rods *i i*, which are connected to the side pieces, A A, as shown at *j*.

The operation is as follows: The seed is placed in the hopper or seed-box B, and, as the machine is drawn along the pins *c* of the wheel D strike the springs F F, the latter being alternately acted upon, owing to the relative position of the pins at both sides of the wheel; and the shaft I is rotated by the action of the pawls G upon the ratchets H H. As the shaft I rotates the teeth *e* discharge the seed from the hopper, forcing them out and insuring a uniform discharge of the seed. By the arrangement of the two pawls and ratchets with the pins *c* the shaft I is rotated continually, one pawl actuating its ratchet while the other is being drawn back. The pawls and ratchets insure a proper or equal movement of the shaft I. Belts are liable to slip, and gearing is objectionable, on account of its being exposed and the number of wheels which would be necessarily required to form a connection between the shaft I and the axle *b* of the wheel D.

I am aware that teeth *e* have been applied to rotating shafts I and arranged, substantially as hereinafter shown and described, to discharge cotton-seed from hoppers, and I do not claim broadly such device; but

I do claim as new and desire to secure by Letters Patent—

The combination of the pins *c* on wheel D, the springs F F, pawls G G, ratchets H H, and toothed shaft I, the latter placed within the hopper B, and all arranged for joint operation as and for the purpose herein set forth.

DANIEL HERLONG.
